US00D800173S

(12) **United States Design Patent** (10) **Patent No.:** **US D800,173 S**
(45) **Date of Patent:** **** Oct. 17, 2017**

(54) **VESSEL PROPULSION UNIT**

(71) Applicant: **YANMAR CO., LTD.**, Chayamachi, Kita-ku, Osaka-shi, Osaka (JP)

(72) Inventors: **Hideo Misao**, Osaka (JP); **Hisanori Mori**, Osaka (JP); **David J. Gruenwald**, Oshkosh, WI (US); **George E. Phillips**, Oshkosh, WI (US); **Bryan L. Danner**, Oshkosh, WI (US)

(73) Assignee: **YANMAR CO., LTD.**, Osaka (JP)

(**) Term: **15 Years**

(21) Appl. No.: **29/573,702**

(22) Filed: **Aug. 9, 2016**

(30) **Foreign Application Priority Data**

Feb. 19, 2016 (JP) D2016-003668

(57) **CLAIM**

The ornamental design for a vessel propulsion unit, as shown and described.

DESCRIPTION

FIG. 1 is a front perspective view of the present invention. FIG. 2 is another perspective view thereof.

FIG. 3 is a front view thereof.

FIG. 4 is a rear view thereof.

FIG. 5 is a top plan view thereof.

FIG. 6 is a bottom plan view thereof.

FIG. 7 is a left side view thereof; and,

FIG. 8 is a right side view thereof.

1 Claim, 8 Drawing Sheets
